LUMINOUS DUPLICATING SYSTEM FOR THE PURPOSE OF SUPERVISING ELECTRICAL DISTRIBUTURING SYSTEMS

Manfred Schleicher, Berlin-Charlottenburg, Germany, assignor to Siemens & Halske, Aktiengesellschaft, Siemensstadt, near Berlin, Germany, a corporation of Germany

Application January 3, 1929, Serial No. 330,127
In Germany January 6, 1928

3 Claims. (Cl. 177—311)

It is well-known that, in order to supervise electrical distributing systems, use is made of luminous duplicating or miniature telltale systems whose sections are illuminated when the corresponding line sections of the distributing system are alive. Such duplicating systems offer, in many cases, an easy survey of the working condition of an electrical distributing system. If, however, great parts of the line system are dead, for instance, if the switch of a main distributing point has dropped, the supervisor can not see from the diagram, up to what point the dead sections are still interconnected. Yet it may be of special importance for him to ascertain this, in case he wishes to reconnect the main distributing point in circuit, for then he must know which sections are hereby made alive and which not.

According to the invention, electrical lamps, for illuminating simulated switches, are therefore fed by means of a circuit which is independent of the circuit for illuminating the sections, so that the illumination of the simulated switches may be made merely dependent on whether the corresponding switch of the distributing system be opened or closed.

A constructional example of the invention is illustrated by the drawing. The general arrangement of the distributing system itself is not shown, since it is exactly simulated by the duplicating system, so that the description of the latter holds also good for the line system of the distributing plant.

Fig. 1 is a diagram of a telltale system embodying my invention; Fig. 2 is a detail view illustrating a suitable arrangement of switches and circuits.

In Fig. 1, I have shown a miniature diagram or reproduction of the distributing system, the numeral 1 designating a symbol which represents the source of current, 2 a symbol representing the line which receives current from said source, and 3, 4, 5, 6 symbols which represent correspondingly arranged line sections of the distributing system. The switches are represented by symbols such as the circles 7, 8, 9, 10, 11, 12. The symbols 1 to 12 represent in a miniature replica, the relative arrangement of the corresponding parts of the distributing system. For illuminating the line section symbols 2, 3, 4, 5, 6, I have provided lamps 22—26 connected, in the

manner shown, with an auxiliary system which likewise is modelled on the distributing system and fed by a current source 13. The lamps 22—26 are controlled by auxiliary switches 37—42 located adjacent to the switch symbols 7—12. The second or return conductors to the lamps 22—26 are connected to the second pole of the current source 13 and have been indicated as a network designated by the numeral 14. The symbols 7—12 indicate in a suitable manner, the position or condition of the corresponding switches in the distributing system. In the working condition which has been taken as a basis for the constructional example shown in Fig. 1, the switches in the distributing system which correspond to the switch symbols 7, 8, and 11, and correspondingly the switches 37, 38, and 41 of the auxiliary or lamp system are also closed. Hence only the sections 2 and 3 are alive, so that only the lamps 22 and 23 illuminating said sections are supplied with current. The sections 4, 5 and 6, however, are dark, and the supervisor would not be sure whether, in case of the sections 4 or 6 being cut in, the section 5 would also be made alive or not. To overcome this difficulty, I have provided a second auxiliary system in which there are arranged, adjacent to the switch symbols 7—12, illuminating lamps 27—32 respectively, which are all fed from the point 33, connected with the current source 13. Between this point and the several lamps 27—32, I have shown switches 47—52 each of which is operated simultaneously with the corresponding switch 37—42 in the first auxiliary system, say coupled mechanically with it, as indicated in the diagram Fig. 2.

The switches of the system shown in Fig. 1 are either operated by a supervisor, to whom each switching in the distributing system is announced, or said switches are operated automatically with the aid of a remote control device. An arrangement suitable for this purpose is indicated in Fig. 2. In order to avoid crowding of lines, the mechanical coupling of the switches has not been indicated in Fig. 1; even so, Fig. 1 shows that the two telltale switches associated with each of the line switches are always in the same position; that is, the switches at 37, and 47 are shown closed as are also the switches at 38 and 48 and the switches at 41 and 51, the

other sets of two switches being shown in the open position. The black circles in the switch symbols 7, 8, and 11 indicate that these are illuminated by the respective lamps 27, 28, and 31. The return conductor of the lamps 27 to 32 is connected through the network 14 with the second pole of the current source 13.

Fig. 2 shows the mechanical coupling or connection between the switches 40 and 50 and it will be understood that the illustration is typical of one pair of associated switches and that the other pairs might be constructed and connected in the same way. The switches 40 and 50, which are associated with the line section symbol 5 and with the switch symbol 10 respectively, are mounted on the same pivoted arm 62, which is constructed as an armature adapted to be attracted in one direction or the other by the relays 60 and 61 energized by batteries 15, 16 respectively. By wires 17 and 18 respectively, the relays 60 and 61 are connected with contacts on a stationary disk 64 adapted to be engaged by a contact arm 63 mounted to rotate about the center of said disk 64. The disk 64 is located at the station at which the apparatus of Fig. 1 is located, and by a line 67, the contact arm 63 is connected with a similar contact arm 65 located in the neighborhood of the switch 100 of the distributing system 104, 105. The arm 65 co-operates with a series of stationary contacts on a disk 66 and two of these contacts are connected by wires 19 and 20 with stationary contacts 102, 103 respectively adapted to be engaged by a switch 101 which is movable in unison with the switch 100 of the distributing system. The switch 101 is adapted to engage, at the same time with the contacts 102, 103, grounded contacts 106 and 107 respectively. The switch arms 63 and 65 are operated to rotate synchronously by any well known or approved mechanism, and the relative location of these arms and of the contacts, is such that the arm 63 will be in conducting connection with the wires 17 and 18 respectively at the same time that the arm 65 is in conducting connection with the wires 19 and 20 respectively. It will be understood that the arms 63, 65 also control the connections of other relays such as 60, 61, the contacts of the disks 64, 66 which are shown unconnected in Fig. 2, being connected with other relays similar to 60, 61 to operate pairs of switches such as 40, 50 in connection with the other switch points of the installation indicated in Fig. 1. Fig. 2 shows that when the arm 62 is attracted toward the right it will close simultaneously the circuits controlled by the switches 40 and 50 respectively. When the arm 62 is attracted toward the left as illustrated said circuits are opened.

In the working condition shown in Fig. 1, the simulated switch or switch symbol 10 is dark, whereas the simulated switch or switch symbol 11 is illuminated. Though switch symbol 11 is placed between line section symbols indicating dead line sections, the switching operator's attention will immediately be drawn to its final position, because it is illuminated. He knows that the line section corresponding to symbol 5 would be made alive, by cutting in the line switch corresponding to symbol 12, but not by closing the line switch corresponding to symbol 9. The invention permits, of course, of rendering conspicuous also the opened switches, though it is doubtful whether a better survey will be obtained thereby. Instead of cutting out the lamps for illuminating the switches, by interruption of

current, one may also cover them by shutters; furthermore, it is also possible to mark the different positions of the switches by different illumination, for instance, in different colours or the like.

In order to mark the working condition of the sections and switches it is not absolutely necessary to illuminate the simulated sections by means of lamps. These may be substituted by electrically operated devices, which cover the simulated network entirely or in part, such as blinds, which according to their positions, render conspicuous parts of different colour or cover them. As to the carrying into effect of the invention, such devices are as useful as the lamps described.

I claim

1. The combination of an electrical distributing system comprising a source of current, line sections, and switches, with a miniature reproduction of said system, such reproduction including line section symbols and switch symbols; lamps for illuminating said symbols; another miniature reproduction of said distributing system, such second reproduction comprising a source of current, electrical conductors, and auxiliary switches, in a relative arrangement corresponding to that of the source of current, line sections, and switches of the distributing system, connections, controlled by said auxiliary switches, between said second reproduction and those lamps which illuminate the line section symbols, to supply current to said lamps according to the position of the auxiliary switches of such second reproduction; additional switches, each operatively associated with one of the auxiliary switches of the second reproduction, and connections, controlled by said additional switches, to supply current to those lamps which illuminate the switch symbols, according to the position of the respective additional switches; and connections whereby said operatively associated pairs of switches are connected with the corresponding switches of the distributing system; the circuits which control the lamps illuminating the switch symbols, being independent of the circuits which control the lamps illuminating the line section symbols, so that the switch symbols will be illuminated solely according to the position of the respective switches of the distributing system, irrespective of the electrical condition of the line sections of said system.

2. The combination of an electrical distributing system comprising a source of current, line sections, and switches, with a miniature reproduction of said system, such reproduction including line section symbols and switch symbols; lamps for illuminating said line section symbols, other lamps for illuminating said switch symbols; electric current receiving connections leading to the first-mentioned lamps, independent electric current receiving connections leading to said second-mentioned lamps; and means for controlling said connections according to the position of the switches in the distributing system.

3. The combination of an electrical distributing system comprising conductors, switches and a source of current with a luminous reproduction of the conductors, switches and source of current of said distributing system, a further electrical reproduction of the distributing system consisting of electrical conductors in sections, switches and a source of current, lamps connected with the conductors of the electrical reproduction for illuminating the sections of the luminous reproduc-

tion, the switches of said electrical reproduction being operated in accord with the corresponding switches of the distributing system, lamps located in electrical circuits for illuminating the switch reproductions forming part of the luminous reproduction, said electrical circuits being independent of each other and of the electrical repro-

duction of the distributing system, and auxiliary switches for controlling the last named lamps, said auxiliary switches being operated in accord with the corresponding switches of the distributing system.
